CHRISTOPHER J. MOGAN AND RICHARD E. BROCK, OF CHARLEROI, PENNSYLVANIA,
ASSIGNORS TO PITTSBURGH STEEL PRODUCTS CO., OF PITTSBURGH, PENNSYLVANIA,
A CORPORATION OF PENNSYLVANIA.

METHOD OF FORMING AXLE-HOUSINGS.

1,091,751.

Specification of Letters Patent. Patented Mar. 31, 1914.

Application filed March 12, 1913. Serial No. 753,827.

To all whom it may concern:

Be it known that we, CHRISTOPHER J. MOGAN and RICHARD E. BROCK, citizens of the United States, and residents of Charleroi, in the county of Washington and State of Pennsylvania, have invented a new and useful Improvement in Methods of Forming Axle-Housings; and we do hereby declare the following to be a full, clear, and exact 10 description thereof.

Our invention relates to a method for making axle-housings for automobiles.

The invention may be said to relate more particularly to making rear axle-housings 15 for automobiles in which the axle-housing is provided at the mid-portion with an enlargement for forming a housing for the gearing.

The object of our invention is to provide 20 an axle-housing of this character made of a section of tubing either seamless or butt or lap-weld, so that it is an integral structure not made up of separate parts, and therefore much stronger and more durable.

Our invention consists, generally stated, 25 in taking a section of tubing having a slotted flattened portion, expanding the metal at the slot outwardly in opposite directions, thereby forming a swell on opposite sides of 30 the axle and forming a housing to receive the gearing and the axles.

In the accompanying drawing, we have illustrated the several steps of our improved method in which—

Figure 1 represents a suitable section of tubing from which the axle may be formed; Fig. 2 shows the end portions of the tubing slightly reduced; Fig. 3 shows the same section with the portion intermediate the reduced ends flattened at opposite sides to 35 form a substantially rectangular cross section and with slots formed in two of the opposite sides of said flattened portion; Figs. 4, 5 and 6 show end views of Figs. 1, 2 and 40 3; Fig. 7 is a view of suitable apparatus for giving the initial stretch to the metal at the slotted portion of the tube; Fig. 8 is a view of a suitable die and former for giving the 45 final shape to the axle; Fig. 9 is a like view showing the metal expanded to fill the die; and Fig. 10 is a view of the finished axle.

50 In carrying out our improved method, we prefer to start with a section of tubing such as illustrated in Figs. 1 and 4, and marked

with the numeral 2. This is preferably a 55 section of drawn seamless steel tubing hot finished or cold, and of suitable diameter and gage. The end portions 3 of the section of the tube are reduced as shown in Figs. 2 and 5. This reduction may be accomplished by passing the end-portions through a die and then backing the die off the tube leaving the mid-portion 3 of the original 60 diameter and shape. The blank 2 is then introduced into a suitable die which reforms 65 the circular portion 3 into the substantially rectangular portion 4, as shown in Figs. 3 and 6, and slots 5 are formed in said squared portion in two of the opposite sides thereof. The axle-housing blank in this form is then 70 operated on by the machine shown in Fig. 7 which comprises the cylinders 6 with the plungers 7, and connected to said plungers are the expanders 8 which have the inwardly 75 projecting portions 9 which are adapted to enter the slots 5 of said axle-housing blank. When introduced into the slots as shown in Fig. 7, the plungers 7 move inwardly in the cylinders and the expanders act to stretch or expand the metal out into substantially 80 the shape shown in Fig. 8, the slot being widened and oblong in form. The housing axle-blank is then inserted in a suitable die 10 with the matrix 11 conforming to the shape which is to be imparted to the central 85 portion of the axle-housing and when inserted in this die, the formers 12 and 13 are 90 inserted in the matrix of the die, the inner end of the former 12 engaging the metal as indicated in Fig. 8, and the formers 13 inserted to move longitudinally of the blank. When the blank has been inserted in the die in this manner, a wedging-tool 14 of suitable construction is inserted and driven inwardly, so as to force the forming blocks 12 95 outwardly, expanding the metal out in the matrix 11 to conform with the shape thereof while the forming blocks 13 are moved slightly longitudinally of the blank to give the proper shape to the metal, so that when 100 the expanding is completed the finished axle-housing will have the appearance shown in Fig. 10, the extreme end portions 15 having been reduced by swaging. In this manner we provide an axle-housing of the character 105 indicated having the enlarged central portion with the opening therein and forming a housing for the differential gears, the axle-

housing being formed of a single piece of metal, which is preferably tubular in form, whether we start with the tube in the form shown in Fig. 1 or whether the tube is originally made up in the form shown in Fig. 3 or other shape. By making the axle-housing of a single piece of hot finished or cold drawn seamless tubing, there is no line of weld in the axle-housing, and consequently a very strong, durable axle-housing is provided which has no weak points.

What we claim is:

1. The method of making axle-housings, consisting in forming slots in opposite sides of a flattened portion of a tubular blank, and stretching the metal outwardly at the slotted portion thereby forming an enlargement.
2. The method of making axle-housings, consisting in slotting the opposite sides of a flattened portion of a tubular blank, and stretching the metal from within outwardly from both sides of the slotted portion, there-

by enlarging the slot and projecting the metal to points beyond the original outlines 25 of the flattened portion.

3. The method of making axle-housings, consisting in slotting opposite sides of a flattened portion of a tubular blank, enlarging said slot to form an oblong opening, 30 and finally applying a force from within to further stretch the metal thereby forming a rhomb-like opening with rounded apices.

4. The method of making axle-housings, consisting in slotting a tubular blank, and stretching the metal outwardly from both sides of the slotted portion, thereby forming an enlargement.

In testimony whereof we, the said CHRISTOPHER J. MOGAN and RICHARD E. BROCK, 40 have hereunto set our hands.

CHRISTOPHER J. MOGAN.
RICHARD E. BROCK.
